UNITED STATES PATENT OFFICE.

GEORG ULLRICH, OF MAGDEBURG, GERMANY.

MAGNETIC SEPARATOR.

1,072,276.

Specification of Letters Patent. Patented Sept. 2, 1913.

Application filed January 12, 1912. Serial No. 670,937.

To all whom it may concern:

Be it known that I, Georg Ullrich, a subject of the King of Bavaria, and resident of Magdeburg, German Empire, have invented certain new and useful Improvements in or Relating to Magnetic Separators, of which the following is a specification.

Magnetic separators are already known in which magnets are arranged in a circle 10 around a vertical axis and over which a magnetizable ring rotatable about the said axis revolves and acts as a common armature and counter pole for the said magnets. The material to be treated is conducted through the 15 field gaps of the several magnetic fields, and the magnetic material is attracted by the rotating ring and conducted out of the magnetic fields so that it falls into the space between two adjacent magnetic fields. In 20 these known devices it has been found that powerfully magnetic material such for example as magnetite or roasted sparthy iron-stone on passing through a magnetic field is not only influenced by the upper rotat- 25 ing magnet pole but also by the lower fixed magnet pole to such an extent that it accumulates on the conveyer medium which supplies the raw material in the magnetic field. On the passage of the material 30 through the field gap it is also not possible to treat simultaneously material in pieces of essentially different sizes. The same applies to material to be treated in large pieces for example when their size exceeds 7 mm.

35 The present invention has for its object to obviate these defects and this object is attained in the following manner: In addition to the magnetizable ring forming the common armature and counter pole for the 40 fixed magnets, a second but non-magnetizable rotatable ring protects or shields the magnets and the field gaps of the magnetic fields from the material under treatment. The rings can be connected one with the 45 other or may be rotatable independently of each other about a common axis. In the latter case they may be given different speeds of rotation.

50 Constructional forms of the apparatus for carrying the invention into effect are illustrated in the accompanying drawing in vertical section in Figs. 1, 2 and 3. The construction illustrated in Fig. 1 will first be described.

55 A plurality of magnets *b* having a common core *a*, are arranged in a circle about

a vertical axis; in the construction here illustrated each of these magnets is energized by a coil *c*. A shaft *d*, the axis of which coincides with the axis of the magnets, can be rotated by any convenient gear such as bevel wheels *e f* and carries at its upper end a disk-shaped body *g*. On the downwardly bent edge *h* of the body *g* a magnetizable ring *i* is fixed and in the known manner serves as a common armature and counter pole for the magnets *b*. The ring *i* carries a second but non-magnetizable ring *k* which covers the magnets *b* and the field gaps of the several magnetic fields relatively to the device supplying the raw material to be treated. Feed channels *m* serve for supplying the material to be treated and they are distributed in such a manner that a channel *m* is provided for 75 each magnet *b*. The feed channels can if necessary receive a shaking or rocking movement from any suitable means not shown in the drawing.

The operation of the apparatus is as follows: The material to be treated is conducted to the feed channels *m* in any appropriate manner and thus conveyed to the several magnetic fields. The magnetic material is then simultaneously attracted by 85 both poles, (the magnet pole *b* and the counter pole *i*) of each magnetic field. While the non-magnetic material slides down at the lower end of each channel *m* the magnetic material collects on the rings *i* and *k* and is thereby carried out of the several magnetic fields and falls into the space between two adjacent magnets *b*. A further advantage of the separator lies in the fact that the field gap can be modified 95 by raising or lowering the upper magnet, and the strength of the field can thus be regulated without changing the strength of the current, and the poles might thus be set very closely together.

In the construction illustrated in Figs. 2 and 3 the non-magnetizable ring *k*² and *k*³ respectively which covers the field gaps and the magnets relatively to the material under treatment, is mounted rotatably about 105 the same axis independently of the magnetizable ring *i*². The said ring is carried by a plate *n* which is rotatably mounted on the shaft *d* and is mounted above the plate *o*² carrying the magnetizable ring *i*². The 110 plate *n* and the shaft *d* are revolved at different speeds by means of a differential

gear p , q , r , s ; in the constructions illustrated the shaft d carrying the magnetizable ring i^2 rotates at a lower speed than the plate n carrying the non-magnetizable ring k^2 or k^3 . The non-magnetizable ring k^2 or k^3 here covers both the magnetizable ring i^2 and the magnets b^2 or b^3 and this arrangement of the ring k^2 or k^3 prevents magnetic material from entering the field gap between the two rings. The magnetic material therefore merely collects on the non-magnetizable ring k^2 or k^3 .

The construction illustrated in Fig. 3 is employed when the poles are arranged immediately one above the other. The constructional form of the ring illustrated in Fig. 2 is applicable to a pole arrangement similar to Fig. 1.

From the foregoing it will be seen that the invention not only obviates any harmful influence of the lower magnet poles b , b^2 or b^3 respectively of each magnet field but even causes these poles to assist in the attraction of the magnetic particles. The non-magnetizable ring k , k^2 or k^3 , prevents magnetic material from becoming deposited on the lower fixed poles b , b^2 or b^3 or entering the field gaps. As the width of the field gap of each of the magnetic fields is independent of the size of the particles, the height of the field gap can be small so that a strong magnetic field is produced with a relatively small consumption of current. Consequently material to be treated in pieces of different sizes (for example from the finest grains up to say pieces of 50 mm.) can be treated simultaneously without the necessity of altering the width of the field gap. While the coarse pieces remain in the magnetic field they are seized and carried by both poles of each field—directly by the upper pole (armature ring ℓ) in the construction illustrated in Fig. 1; by the lower pole (magnet b) through the intermediary of the ring k covering this pole; in the construction shown in Figs. 2 and 3, by both poles through the intermediary of the ring k^2 or k^3 . The position of the feed device can either be selected in such a manner that the path of the material supplied crosses the path of the separated magnetic material in any direction or so that both paths run parallel either in the same direction or in opposite directions.

It should be noted that separators embodying the invention are adapted both for wet and for dry treatment.

Having thus described my invention, what I claim as new therein and desire to secure by Letters Patent is:

1. In a magnetic separator, a stationary magnet, a non-magnetic guard entirely covering the active part of said magnet and against which guard the material is held by the magnet, said guard rotating to re-

move the adhering material when beyond the action of said magnet, a counter-pole adjacent to said magnet also attracting the material, said counter pole also constructed to rotate.

2. In a magnetic separator, a stationary magnet, a non-magnetic guard in front of said magnet against which the material is held by the magnet, means for rotating said guard to remove the adhering material when beyond the action of said magnet, a ring-shaped counter-pole adjacent to said magnet also attracting the material, and gearing for said counter-pole, said gearing being actuated by said rotating means and constructed to rotate said counter-pole at different speed from that of said guard.

3. In a magnetic separator, a stationary magnet, a counter-pole adjacent said magnet, a guard against which the material is held by said magnet and said pole, said guard overlapping both the magnet and the counter-pole and means for rotating said guard in order to remove the adhering material when beyond magnetic action; a gearing for said counter-pole constructed to rotate the counter-pole at a different speed from said guard.

4. In a magnetic separator, a plurality of electro-magnetic stationary poles of the same polarity arranged symmetrically around a common vertical axis, the coils for said poles having their axes arranged radially in a common horizontal plane, a rotating guard, an annular rotary counter-pole of opposite polarity to said stationary poles and suitable rotary carrying means for said guard and counter-pole mounted coaxially with said stationary poles, said guard adapted to conduct the material under treatment away from said stationary poles.

5. In a magnetic separator, a plurality of magnetic stationary poles arranged symmetrically around a common axis, a rotating guard, an annular counter-pole and suitable rotary carrying means for said guard and said counter-pole mounted coaxially with said first named magnetic poles; said guard located above and extending downwardly outside of said counter pole.

6. In a magnetic separator, a plurality of magnetic stationary poles arranged symmetrically around a common axis, a rotating guard, an annular counter-pole and suitable rotary carrying means for said guard and said counter-pole mounted coaxially with said first named magnetic poles; said guard located above and extending downwardly outside of said counter-pole and covering the field gap between the poles and the counter-pole.

7. In a magnetic separator, means for producing a plurality of magnetic fields arranged symmetrically around a common

axis, said means including two poles arranged one beneath the other for each field, the lower pole being stationary and the upper pole rotary, an annular carrying member situated outside of said poles and covering the field gap, said carrying member being revoluble around said common axis, one of said poles being axially adjustable relative to the other, whereby the field gap may be regulated thus changing the strength of 10 the magnetic field.

The foregoing specification signed at Magdeburg this 21st day of December, 1911.

GEORG ULLRICH.
